UNITED STATES PATENT OFFICE.

MILTON WEIL, OF NEW YORK, N. Y.

MANUFACTURE OF HOSIERY AND OTHER KNIT ARTICLES FROM RAW SILK.

1,238,607.

Specification of Letters Patent. Patented Aug. 28, 1917.

Application filed December 6, 1916. Serial No. 135,360.

To all whom it may concern:

Be it known that I, MILTON WEIL, a citizen of the United States, and a resident of the city of New York, borough of Manhattan, in the county and State of New York, have invented certain new and useful Improvements in the Manufacture of Hosiery and other Knit Articles from Raw Silk, of which the following is a full, clear, and 10 exact description.

The object of the invention is to provide certain new and useful improvements in the manufacture of knit hosiery and other knit articles from raw silk whereby the spinning 15 or throwing of the silk is entirely dispensed with and the hosiery produced is of the desired density without an increase in the number of raw silk ends used for each knitting member or strand.

In the manufacture of knit silk hosiery as heretofore practised, it has been customary to spin one or a number of raw silk ends (anywhere from 5 to 25 ends) into a 20 twisted thread (including singles, tram and organzine), to wind the twisted thread onto a spool or the like and then to feed the twisted thread to the thread carrier and to the knitting elements of a knitting machine to form the knitted fabric. It will be noticed 25 that the practice of spinning or twisting the raw silk ends into a twisted thread involves considerable expense but has heretofore been deemed necessary in order to insure the strength and firmness of the knit article and 30

to allow proper unwinding of the twisted thread from the spool and feeding of the thread practically tensionless to the knitting elements. The feeding of loose, non-twisted 35 ends to the knitting elements of a knitting

40 machine has heretofore not been carried out, as it was considered impracticable to unwind loose, non-twisted ends from a spool and feed the same to the knitting elements without producing entanglement of the loose

45 ends. In a companion application for an attachment for high speed winders, Serial No. 135,359, filed December 6, 1916, I have shown and described a mechanism by which the non-twisted raw silk ends are unwound

50 from the spool and fed in this non-twisted condition and with little tension to a winding machine or directly to the thread carrier and knitting elements of a knitting machine.

55 My present invention consists in a method whereby the ends of raw silk are doubled to

form what I prefer to term a "knitting member" having a plurality of the ends in untwisted relation and then forming the knitting member into knitted interlocking 60 stitches with the raw silk ends remaining in untwisted relation. My invention further consists in a new article of manufacture, namely, knit hosiery or the like, formed of a knitting member which consists of a plurality of ends of raw silk in untwisted relation to each other, the knitting member being formed into interlocking stitches with the raw silk ends remaining in untwisted 65 relation.

In order to accomplish the desired result in detail, I proceed as follows, special reference being had to the accompanying drawings, in which—

Figure 1 is a side elevation of the apparatus for carrying the method into effect, parts being shown in section;

Fig. 2 is a sectional plan view of the same on the line 2—2 of Fig. 1; and

Fig. 3 is an enlarged side elevation of a 80 portion of the knit fabric.

A number of raw silk ends arranged one alongside the other form a non-twisted knitting member 10 unwinding from a spool 11 removably mounted on a vertically disposed 85 spindle 12 fixed at its upper end to a suitable overhead support 13 directly above the knitting machine. The bottom flange of the spool 11 rests on a key 14 pivoted at 15 to the spindle and adapted to swing into alignment with the spindle whenever it is desired to remove an empty spool from the spindle 12 and place a filled spool on the spindle 12. It is understood that after the spool is 90 slipped onto the spindle 12 the key 14 is 95 swung into right-angled position relative to the spindle 12 to support the spool 11 on the spindle. The knitting member 10 after unwinding from the spool 11 passes through an eye or similar guide 16 held on the lower 100 end of an elastic band 17 attached at its upper end to an eye 18 of a flexible fier arm 19 terminating in a coil 20, the end of which is fastened to an arm 21 of a hub 22 shown in the form of a heavy coil of wire loosely 105 encircling the spindle 12 and resting on a collar 23 formed on the spindle a short distance above the top of the spool 11. The knitting member 10 after leaving the eye 16 passes through a thread guide 25 located 110 centrally below the spindle 12 and above a winding machine or a knitting machine to

be formed into knit interlocked stitches for producing a knit article in which the knitting member 10 is formed of non-twisted raw silk ends. By taking the untwisted 5 knitting member 10 off the spool by way of the thread guide 16 held on the elastic band 17 the ends of the knitting member are not liable to become entangled. It is understood that when the knitting member 10 is passed 10 to a winding machine it is wound up on a cone, cop, tube, bobbin or similar spool device, to be subsequently used on the knitting machine for delivering the knitting member to the thread carrier and the knitting elements 15 of the knitting machine, but, as above stated, the knitting member 10 may be directly fed to the thread carrier of a hosiery knitting machine.

From the foregoing it will be seen that 20 by the arrangement described knit hosiery or other knit article is formed of a knitting member of untwisted raw silk ends, which latter remain in untwisted condition on the knit article.

25 It will be noticed that by manufacturing hosiery in the manner described, the expense of twisting or throwing is entirely dispensed with and the hosiery produced is of a denser quality without increase in the number of 30 the raw silk ends for each knitting member. The strength of the hosiery is not impaired on account of not twisting the raw silk ends.

It will also be noticed that by leaving the 35 raw silk ends untwisted more density is given to the fabric, considering the number of raw silk ends in a twisted thread to be the same as in the untwisted knitting member 10.

Having thus described my invention, I claim as new and desire to secure by Letters 40 Patent:—

1. The herein described method of manufacturing hosiery from raw silk, consisting in doubling ends of raw silk in the natural state to form a knitting member having the 45 ends in untwisted relation, and then forming the knitting member into knitted interlock-

ing stitches with the raw silk ends remaining in untwisted relation.

2. The herein described method of manufacturing hosiery from raw silk, consisting in doubling a plurality of ends of raw silk in the natural state to form a knitting member, delivering the knitting member to the knitting elements of a knitting machine, and then forming the knitting member into 55 knitted interlocking stitches with the raw silk ends remaining in untwisted relation.

3. As an article of manufacture, raw silk knit hosiery, made wholly of a knitting member which consists of a plurality of ends 60 of raw silk in the natural state and in untwisted relation to each other, the knitting member being formed into interlocking stitches with the raw silk ends remaining in untwisted relation. 65

4. The herein described method of manufacturing hosiery from raw silk, consisting in arranging a plurality of raw silk ends one alongside the other in untwisted relation to form a single strand, winding the strand on 70 a spool, maintaining the raw silk ends of the strand in untwisted relation while exerting a pull on the strand to unwind the strand from the spool and while guiding the strand through guiding means capable 75 of flexing and stretching and receding from or approaching the spool, and finally delivering the strand to the knitting elements of a knitting machine to knit the strand into interlocking stitches with the raw silk ends 80 of the strand remaining in untwisted relation.

5. As an article of manufacture, raw silk knit hosiery which consists wholly of a single strand formed of a plurality of raw 85 silk ends in the natural state and in untwisted relation to each other and knitted into interlocking stitches with the raw silk ends of the strand remaining in the natural state and in untwisted relation.

MILTON WEIL.
